1

The present invention relates to straight knitting machines, with draw-off or welt rods housed in magazines, and more particularly to a method and an apparatus for inserting the draw-off or welt rods into the knitted fabric manufactured on straight knitting machines.

The methods hitherto known for inserting the welt or draw-off rods are automatic in part only, and moreover are relatively complicated and require careful assistance. The assistant has to bring each of the welt rods, during the operation of the machine, by hand to a preparatory position, from which the rod is removed, either by hand or automatically, and placed in front of the hooks of the draw-off device.

More recently an arrangement for inserting the welt rods has been proposed which represents an improvement over the prior arrangements in that instead of placing each welt rod by hand in preparatory position, a set of welt rods are introduced at a time into magazines which are located on either side of the needle bank above the combs for the picot edge. From the magazines, the individual welt rods are advanced by a special device first to a preparatory position, i. e. into special holders fastened directly on the picot edge combs. During the knitting of a part of the double welt of a stocking the assistant moves by hand the picot edge comb to its operative position, i. e. above the knitting needles, whereby also the holders with the individual welt rods are transferred from their preparatory position to a position in front of the hooks of the draw-off belts. By a vertical idle stroke of the narrowing device, and thus also of the picot edge combs, in the direction towards the knitting needles and by the back stroke to inactive position, i. e. away from the knitting needles, the ends of the welt rods are taken automatically out of the holders by the hooks of the draw-off device and are drawn away from the needles by the knitted fabric.

This method of inserting the rods requires, in addition to the manual operations, a special device for transferring the individual rods from the magazines to the auxiliary holders on the picot edge combs, and further requires turning them by hand from the preparatory position and then imparting lateral movement to the main cam shaft with vertical movements of the whole of the narrowing device and thus also of the picot edge combs in idle strokes, and finally the use of another device for putting out of action the lateral motion of the picot edge combs. Due to the idle movement in a downward direction of

2

the picot edge combs, the narrowing needles are caused to come in contact between the sinkers with the knitting needles and with the meshes hung on the same, causing the meshes to be tensioned without transferring them sidewise. The construction of the machine as a whole becomes complicated, apart from the greater effort of the assistants and responsibility required from them.

10 If the assistants have a plurality of machines with a small number of needle banks entrusted to their care, the knitting operations of the individual machine are not synchronous, so that it is necessary to put in operation by hand the picot edge combs and thus introduce the welt rods at different moments, whereby particular care is required on the part of the assistant since by failing to put in operation the picot edge combs and with them the welt rods, ware of

20 lower quality may be produced.

25 The invention disclosed hereinafter permits to eliminate the above mentioned disadvantages, and consists substantially in causing the welt rods, which have been introduced at any desired time into a magazine, to occupy successively and quite automatically their working position in front on the hooks of the draw-off device. Thereby the assistant's work is considerably simplified since the assistant, who needs not be particularly skilled, merely has to pull out the rods from the finished ware and to introduce them again in the magazines at any desired time. In addition, the output of the machines is increased and a larger number of machines 30 may be entrusted to a single assistant, thereby considerably reducing the manufacturing cost.

35 The drawings show by way of example an embodiment of the invention.

Fig. 1 is a cross-sectional view of the apparatus 40 along the line 1—1 of Fig. 4, the apparatus being shown at the moment when the draw-off or welt rods are in inoperative position and the knitted fabric is being drawn away directly by the hooks of the draw-off device;

Fig. 2 is a detail view corresponding to Fig. 1, but showing the welt rods in their working position, the lowermost rod having been withdrawn from the magazine by the hooks of the draw-off device;

Fig. 3 is a view similar to Fig. 2, but the remaining welt rods are shown again out of their working position, the lowermost rod together with the knitted fabric being pulled away by the hooks of the draw-off device;

Fig. 4 shows the apparatus in elevation as

viewed in the direction of the arrow S shown in Fig. 1, and the magazine in section along the line 4—4 of Fig. 1, with the welt rods in their inoperative position;

Fig. 5 is a detail view of a part of Fig. 4 and shows at a larger scale the right hand magazine in inoperative position with the chamber opened, and the feeding device;

Fig. 6 is a cross-sectional view of the magazine and the chamber along the line 6—6 of Fig. 4; 10

Fig. 7 is an axonometric view of the driving device for the apparatus; and

Fig. 8 is a detail view at a larger scale showing the switching or change-over lever.

The apparatus shown for carrying out the method of the invention is mounted on a straight knitting machine of which only the knitting needles 1, the cooperating sinkers 2, the knitted fabric 3, and the draw-off hooks 4 of a comb 5 are shown in Figs. 1 to 3. The comb is moved by means of a roller 6 and a spring 7 connected at its both ends to the said comb 5, as may be seen in Fig. 1. In the working table 8 there is mounted a transverse shaft 9 provided with a holder 10 on either side of the needle bank, the holders 10 having chambers 11 fastened thereon, as is shown also in Figs. 4 and 7. Magazines 12 may be displaced within said chambers under the action of a feeding device, as shown in Fig. 5. To make the access more easy, each chamber is provided with a lid 14, as shown in Fig. 4. Each magazine 12 is provided with a groove 13, as is shown more clearly in Fig. 6, for guiding the ends of the draw-off or welt rods 15 which are in contact with each other by means of their spacing rings 16 so as to leave a gap 17 of sufficient size between adjacent rods, as may be seen in Fig. 5. The lowermost rod bears with its ends against the bottom of the groove 13 on the magazine 12. The number of the superposed welt rods 15 depends on the size of the magazine and may be chosen according to requirements in any particular case. In another groove 18 provided in the magazine 12 opposite to the longitudinal groove 13, as is shown in Fig. 5, a locking member 20 is mounted on a fulcrum 19, a pin 21 provided on the locking member being guided in a groove 22 of the chamber 11, as is shown in Fig. 4. The free end of the locking member 20 is formed as a nose 23 (Fig. 5) which under the pressure of a flat spring 24 fastened to the magazine, engages for a time into the gap 17 between the end of the lowermost draw-off rod and the end of the adjacent rod.

The feeding device for advancing the magazines and their welt or draw-off rods 15 from the inactive position A to the working position B (Figs. 4 and 5), and in reverse direction, comprises a small single arm lever 25 mounted for rocking movement on a fulcrum 26 in the chamber 11. A flat spring 27, fastened with its one end to the inner wall of the chamber 11, exerts pressure by its free end on the single arm lever 25, as is shown also in Fig. 6. The free rounded end 28 of the lever 25 engages in a recess 29 formed in the magazine 12, as is shown more particularly in Fig. 5; the lever 25 is provided with a longitudinal groove 30 to receive a driving pin 31 secured to the end of a link 32 mounted movably in the chamber 11. The opposite end of the link 32 is guided in a groove provided in a small single arm lever 33 by means of a pin 34, as is shown in Figures 1, 4 and 7. The small lever 33 is fastened on a shaft 35 which is mounted loosely in holders 36 secured to the

transverse shaft 9 adjacent to the side members 37, as is shown more particularly in Figs. 4 and 7.

One end of the shaft 35 has fastened thereon a small holder 38 provided with a pin on which one end of a tension spring 39 is secured, the other end of the spring being held by a hanger 40 fastened in the holder 36. A pin 41 screwed into the end face of the transverse shaft 9 carries rotatably a single arm switching or change-over lever 42, as is shown also in Fig. 8, the free end of the lever being formed as a nose 43. In the arm of the lever 42 there is mounted a pin 44 with a head 45 for securing a steel strip 46 which connects the head 45 with the holder 38. Adjustment of the pin 44, and thus of the steel strip 46, is made possible by two nuts 47 on the other end of the pin 44. The hub of the change-over lever 42 is provided in a portion of its periphery with two teeth 48 and 49, and a pawl 50 (Fig. 7) mounted rotatably on a pin 51 screwed in the wall of the holder 36 is adapted to engage alternately with the said teeth 48 and 49. The latter are located in unequal distances from the center of the hub of the lever 42, the tooth 48 being spaced a smaller distance from the center of the hub. The pawl 50 is held against the tooth 48 or 49 by a torsion spring 52 secured to a pin 53 on the holder 36, as is shown in Figures 7 and 8. The arm 54 of the pawl 50 is adapted to be subjected for a time to the action of the bent end 55 of a releasing link 56 which is fastened adjustably by means of screws 57 on a single arm lever 58. In the end of the lever 58, which is fastened on a shaft 59, there is mounted rotatably a pin provided with a head 60 having a notch 61 formed therein to serve as a guideway for a thin rod 62 held firmly in a holder 63. The latter is fastened on the one end of a pin 64 which is mounted rotatably in a small bracket 65 and whose other end has secured thereon a pusher 66 which at a certain time acts upon the nose 43 of the change-over lever 42. The bracket 65 is fastened on a reciprocating slide 67 of the sinker device of the knitting machine, as is shown also in Fig. 1. The sinker mechanism employed is described in detail in the co-pending application, Ser. No. 25,606, filed May 7, 1948, now U. S. Patent 2,571,314, issued October 16, 1951, and is not further illustrated here since its details are not necessary to an understanding of the present invention.

An impulse for the operation of the apparatus in accordance with the present invention is transmitted at the suitable moment from a pattern drum 68 (Figs. 1, 4 and 7) which is rotatably mounted in the side member 37 and has on its periphery a series of cam projections of different heights and lengths, of which a low projection 69 or a high projection 70, for instance, co-operates at a definite time with a small lever 71 mounted for rocking movement about a fulcrum which is not shown. A link 72 connected with the lever 71 has its other end connected to a single arm lever 73 which is fastened to a shaft 59 mounted for free rotation in the side members 37.

Of the set of welt or draw-off rods 15 which are in the working position B shown in Fig. 1, the ends of the lowermost rods resting on the knitted fabric 3 cooperate with the respective hooks 74 (as is shown also in Fig. 2) of the belts 75 of the draw-off device which belts have both their ends fixed to a bar 76 (Fig. 7) connecting the hooks 74. The draw-off belts 75 are guided over rollers 77 (Fig. 1) freely rotatable on holders 78,

which are fastened on the working table 8. The winding and unwinding of the draw-off belts 75 is effected by the draw-off roller 79 and the discs 80.

The apparatus as far described operates in the following manner:

During the time of knitting the first half of the double welt of a stocking, when the apparatus in accordance with the present invention has not yet been put in operation, as is shown in Fig. 1, the knitted fabric is held by the hooks 4 and is pulled away by the comb 5 which is being moved by means of the rollers 6 and springs 7 in the corresponding guideway in a direction away from the needles 1.

At this stage the pattern drum 68 occupies just the position in which the lever 71 rests on a low cam projection 69 (Figs. 1 and 7), so that the pusher 66 carried along by the reciprocating slide 67 does not abut against the nose 43 of the change-over lever 42, and moves without obstruction in the recess of the lever 42, as is shown in Fig. 4. In the same position of the pattern drum 68 the bent end 55 (Fig. 7) of the releasing link 56 is held out of contact with the arm 54 of the pawl 50, and the latter, being urged by the torsion spring 52, engages with the tooth 48 which is spaced a smaller distance from the center of the hub of lever 42.

In the position shown in Fig. 7 the change-over lever 42 through the intermediary of the tensioned steel strip 46, the holder 38, the shaft 35, the lever 33, the link 32 and the lever 25, keeps the magazine 12 with the set of welt rods located in the latter in the inoperative position A (Figs. 4 and 5). The hooks 74 of the draw-off belts 75 at this stage also occupy their inoperative position between the needles 1 and the welt rods 15, as is shown in Fig. 1.

When the picot edge has been completed, or during the following period of knitting the second half of the double welt of a stocking, the apparatus described will be brought into operation by the effect of the pattern drum 68, which is driven by the main cam shaft (not shown). By rotation 45 of the pattern drum 68 in the direction of the arrow in Figures 1 and 7, the lever 71 slips down from a low cam projection 69 on to the periphery of the drum 68. The link 72 connected to the lever 71 is moved downwards and causes the lever 73, the shaft 59 and the lever 58 to turn downwards through a certain angle. Due to the angular movement of the lever 58 also the head 60 together with the rod 62 guided in the slot 61 (as is shown also in Fig. 4) are moved down. As 55 a consequence the holder 63 and pin 64 are caused to turn, thereby deflecting the arm of the pusher 66 away from the nose 43 of the change-over lever 42, as shown in dotted lines in Fig. 4. By the rocking movement of the lever 58 the releasing link 60 is moved down and the bent end 55 of the same comes to bear against the arm 54 of the pawl 50 which becomes disengaged from the tooth 48 of the lever 42. Under the action of the steel strip 46 and the tension spring 39, the holder 38 is 65 caused to turn downwards and the lever 42 rotates toward the holder 38 till the tooth 49 of the lever 42 is brought in engagement with the pawl 50. By the downward rotation of the holder 38 and thus of the shaft 35 with the lever 33, the link 32 is pulled out of the chamber 11 (Fig. 1). By engagement of the driving pin 31 of the link 32 in the longitudinal groove 38 of the lever 25 and under the pressure of the flat spring 27 on the said lever 25, the latter is caused to rock down 75

about the pin 26 (Fig. 5). The magazine 12, being entrained by the rounded end 28 of the lever 25 together with the set of welt rods 15 located in the magazine, is advanced from the inoperative position A to the working position B, as is shown also in Fig. 5. During this movement of the magazine 12, the pin 21 of the locking lever 20 carried along with the magazine slides in the corresponding groove 22 (Fig. 4) of the chamber 11, whereby the nose 23 of the lever 20 under the pressure of the flat spring 24 engages in the gap 17, i. e. between the end 14 of the lowermost welt rod 15 and that of the adjacent welt rod, as is shown in Fig. 5.

15 The tooth 23 of the locking lever 20 separates the lowermost welt rod 15 from the adjacent rod and maintains the rest of the welt rods in the working position B, i. e. in front of the hooks 4 of the comb 5 in the position shown in dotted lines in Fig. 1. On the main draw-off operation being automatically initiated, i. e. by rotation of the draw-off roller 79 in the direction of the arrow in Fig. 1, the draw-off belts 75 are wound up and the hooks 74 are moved towards the draw-off roller 79. The withdrawn hooks 74 seize automatically the lowermost rod 15 and pull it, while still guided in the grooves of the magazines, away from the needles 1 until the rod leaves the magazines (Fig. 2). The rod thus held by the hooks 74 draws off the fabric 3 until the stocking is completely knitted. The comb 5 remains stationary and the leading end of the knitted fabric 3, which end is hung on the hooks 4 of the comb 5, is caused to slide by the tension of the rod 15 along the stems of the hooks 4 towards the comb 5 where the said end bears against the backs of the hooks, as is shown in Fig. 3.

30 Since the set of welt rods 15 occupying the working position B would hinder the automatic hanging over of the double welt, i. e. the free passage of the comb 5 with the leading row of meshes towards the needles 1, the remaining rods must be moved to the inoperative position A, where they should remain until the next insertion step, that is till the welt of the next stocking will have to be knitted.

35 When the lowermost rod 15 has been pulled out of the magazine 12, the apparatus in accordance with the present invention is again operated by the step by step rotation of the pattern drum 68. The lever 71 which rests on the periphery of the drum 68 encounters a high projection 70 whereby the link 72 is moved up and the lever 73, the shaft 59 and the lever 58 are rotated upwards (Figures 1, 4 and 7). Owing to the lever 58 being rocked, the head 60 is moved up together with the rod 62 guided in the slot 61. Turning of the holder 63 and pin 64 takes place, thereby deflecting the arm of the pusher 66 in the direction towards the nose of the lever 42. Due to the movement of the slide 67 of the sinker device towards the commanding drum 68, the arm of the pusher 66 comes to bear against the nose 43 of the change-over lever 42 causing the latter to turn in the direction to the pattern drum 68 till the tooth 48 of the lever engages again with the pawl 50. The steel strip 46 carried along with the lever 42 is tensioned and causes the holder 38, the shaft 35 and the lever 33 to be rotated upwards, so that the link 32 enters the chamber 11. By the link 32 being introduced into the chamber 11 the lever 25 is

caused to rock up about the pin 26 to its original position (Fig. 5). The magazine 12, being carried along by the rounded end of the lever 25 together with the set of welt rods 15, is moved from the working position B to the inoperative position A (Fig. 5). During the just mentioned introduction of the magazines 12 into the chambers 11, the pin 21 of the locking lever 20 slides in the corresponding groove 22 of the chamber 11, thereby causing the nose 23 of the locking lever 20 to be moved against the pressure of the flat spring 24 from within the gap 17 to its original position (Fig. 5). The set of welt rods 15, which until now has been held by the nose 23 of the locking lever 20 in the magazine 12 (Fig. 2), falls to the bottom of the groove 13 of the magazine 12 whereby the rods are in a position ready for further automatic insertion (Fig. 3). The magazines 12, which are gradually emptied during the operation of the knitting machine, are refilled when required by introducing a number of rods at a time. The further step by step rotation of the pattern drum 68 will cause the lever 71 to slip from a high cam projection 70 again on a low projection 69 where it will remain up to the moment when the rods will have to be inserted again in the knitted fabric.

When the second half of the welt has been completed, the comb 5 is moved automatically under the action of the usual mechanism for hanging over the double welt, together with the leading end of the knitted fabric 3, towards the needles 1 and hangs over the first row of meshes on the knitting needles 1. The type of device for automatically hanging over the double welt, with which the machine is equipped, is of no importance for the present invention, and it is also immaterial whether the draw-off combs are arranged in a lying position or in the direction of the axes of the knitting needles.

What I claim is:

1. In a method of inserting the draw-off rods for the double welts of stockings to be knitted on a straight knitting machine having sets of draw-off rods contained in magazines and take-up devices operable to engage draw-off rods in the magazines, which comprises advancing the magazines to position the lowermost draw-off rods therein in the path of the take-up devices and effecting the transfer of the lowermost draw-off rods from the magazines to the welt of the knitted fabric in a fully automatic manner in timed relation with the operation of the knitting machine.

2. In a method of inserting the draw-off rods for the double welts of stockings to be knitted on a straight knitting machine having sets of draw-off rods contained in magazines and take-up devices operable to engage draw-off rods in the magazines, which comprises advancing the magazines to position the lowermost draw-off rods therein in the path of the take-up devices and effecting the transfer of the lowermost draw-off rods from the magazines to the welt of the knitted fabric in a fully automatic manner in timed relation with the operation of the knitting machine and controlling by the movement of the sinker mechanism of the knitting machine the transfer of the magazines with the draw-off rods from their inoperative position to their operative position and vice versa.

3. In a method of inserting the draw-off rods for the double welts of stockings to be knitted on a straight knitting machine having sets of draw-off rods contained in magazines and take-up de-

vices operable to engage draw-off rods in the magazines, which comprises advancing the magazines to position the lowermost draw-off rods therein in the path of the take-up devices and effecting the transfer of the lowermost draw-off rods from the magazines to the welt of the knitted fabric in a fully automatic manner in timed relation with the operation of the knitting machine by a feeding device and a change-over device connected to the latter and adapted to co-operate with a pusher device fastened on the reciprocating slide of the sinker mechanism of the knitting machine and operated by a pattern drum.

4. In a straight knitting machine, an apparatus for inserting the draw-off rods for the double welts of stockings in the process of manufacturing the latter, the apparatus comprising magazines, sets of draw-off rods in the magazines, means for transferring the magazines between inoperative and operative positions, means which during the transfer of the magazines with the draw-off rods from the inoperative into operative positions, are adapted to separate the lowermost draw-off rod of each set from the remaining draw-off rods of that set, and take-up devices, adapted to engage and remove the lowermost draw-off rod from each magazine upon movement of the latter into operative position.

5. In a straight knitting machine, an apparatus for inserting the draw-off rods for the double welts of stockings in the process of manufacturing the latter, the apparatus comprising magazines, sets of draw-off rods in the magazines, means for transferring the magazines between inoperative and operative positions, means which during the transfer of the magazines with the draw-off rods from the inoperative into operative position are adapted to separate the lowermost draw-off rod of each set from the remaining draw-off rods of that set, take-up devices adapted to engage and remove the lowermost draw-off rod from each magazine upon movement of the latter to operative position, and means which during the return movement of the magazines from the operative to inoperative position are adapted to cause the remainder of each of the set of draw-off rods to fall on to the bottoms of the magazines.

6. In a straight knitting machine, an apparatus for inserting the draw-off rods for the double welts of stocking in the process of manufacturing the latter, the apparatus comprising magazines, sets of draw-off rods in the magazines, shifting means for transferring the magazines between inoperative and operative positions, means which during the transfer of the magazines with the draw-off rods from the inoperative into operative position are adapted to separate the lowermost draw-off rod of each set from the remaining draw-off rods of that set comprising locking means carried along with the magazines and adapted to engage for a time between the ends of the bottom two draw-off rods of each set and retain each set of rods above the lowermost one thereof from moving down in the magazine, take-up devices, adapted to engage and remove the lowermost draw-off rod from each magazine upon movement of the latter to operative position, means which during the return movement of the magazines from the operative to inoperative position are adapted to release the locking means to cause the remainder of each of the set of draw-off rods to fall on to the bottoms of the magazines, and means for

controlling the operation of each of the locking means carried along with the corresponding magazine.

7. The apparatus as set forth in claim 6, which further includes chambers within which said magazines are displaced, and wherein the means for controlling operation of each of said locking means is comprised of a profiled groove in a chamber and a pin on said locking means slideable in said groove.

8. In a straight knitting machine, an apparatus for inserting the draw-off rods for the double welts of stockings in the process of manufacturing the latter, the apparatus comprising magazines, sets of draw-off rods in the magazines, shifting means for transferring the magazines between inoperative and operative positions, means which during the transfer of the magazines with the draw-off rods from the inoperative into operative position are adapted to separate the lowermost draw-off rod of each set from the remaining draw-off rods of that set comprising locking means carried along with the magazines and adapted to engage for a time between the ends of the bottom two draw-off rods of each set and retain each set of rods above the lowermost one thereof from moving down in the magazine, take-up devices adapted to engage and remove the lowermost draw-off rod from each magazine upon movement of the latter to operative position, means which during the return movement of the magazine from the operative into inoperative position are adapted to release the locking means to cause the remainder of each of the set of draw-off rods to fall on to the bottoms of the magazines, means for controlling the operation of each of the locking means carried along with the corresponding magazine, and chambers in which the magazines with the sets of draw-off rods in the same are guided and which are arranged on both sides of the needle banks of the knitting machine adjacent to the knitted fabric.

9. The apparatus as set forth in claim 8, in which a shifting device for transferring the magazines with the draw-off rods is mounted on each chamber, a changeover device is provided and links connect the changeover device with the shifting devices.

10. The apparatus as set forth in claim 9, in which the shifting device comprises a single arm locking lever mounted on the said chamber and having its free end in engagement with a recess

in the said magazine, and the connection with the link comprises a groove in the said lever in engagement with a driving pin on the said link.

11. The apparatus as set forth in claim 10, in which said change-over device comprises a rocking change-over lever connected with the link of the shifting device and having a hub provided with two teeth at different spacings from its center, a pawl adapted to engage alternately with the said teeth, said lever provided at its end with a nose, and a pusher device adapted to bear at times against said nose to rock said lever.

12. The apparatus as set forth in claim 11, in which the said pawl by engagement with the teeth of the said change-over lever, which the said pusher device is adapted to deflect at a suitable moment, serves to secure the change-over lever in positions corresponding to the inoperative and operative positions of the magazines for the draw-off rods.

13. The apparatus as set forth in claim 12, in which said pusher device comprises a bracket fastened upon the reciprocating slide of the sinker device of the knitting machine, a pin rotatable about its axis carried by said bracket, a pusher element adapted to bear against the nose of said change-over lever, a holder, said pusher element and holder being mounted rigidly on said pin for rotation about the pin axis, and a rod fastened rigidly to said holder, said rod being disposed laterally of said pin and being movable to rotate said holder and pusher element so as to alternatively clear or bear against said nose.

14. The apparatus as set forth in claim 13 and which further includes a pattern drum having cam projections of different height thereon is provided and in which the cam projections control the rotative position of said pusher element with respect to the nose of the change-over lever so that the pusher element clears the nose when the magazine is to be moved to operative position and engages the nose to actuate the lever to return the magazine to inoperative position after insertion of a draw-off rod.

JAROSLAV VÁCLAVÍK.
